CLAIM

We claim the ornamental design for an insert for a wristband strap, as shown and described.

DESCRIPTION

FIG. 1 is a top view of an insert for a wristband strap.

FIG. 2 is a rear view of the insert for a wristband strap of FIG. 1.

FIG. 3 is a bottom view of the insert for a wristband strap of FIG. 1.

FIG. 4 is a front view of the insert for a wristband strap of FIG. 1.

FIG. 5 is a left side view of the insert for a wristband strap of FIG. 1.

FIG. 6 is a right side view of the insert for a wristband strap of FIG. 1.

FIG. 7 is an isometric view of the insert for a wristband strap of FIG. 1.

FIG. 8 is a reverse isometric view of the insert for a wristband strap of FIG. 1.

FIG. 9 is a side view of the insert for a wristband strap of FIG. 1 shown in the context of where it would be located when part of a first strap for a wristband.

FIG. 10 is a side view of the insert for a wristband strap of FIG. 1 shown in the context of where it would be located when part of a second strap for the wristband.

FIG. 11 is an isometric view of the insert for a wristband strap of FIG. 1 shown in the context of where it would be located when part of the second strap for the wristband; and, FIG. 12 is an isometric view of the insert for a wristband strap of FIG. 1 shown in the context of where it would be located when part of the first strap for the wristband.

Stipple shading has been provided to illustrate surface contours and does not indicate texture. The broken line shown in FIGS. 1-8 illustrate portions of the insert for a wristband strap that form no part of the claimed design. The broken lines shown in FIGS. 9-12 that show a first and second strap of a wristband illustrate environmental structure that forms no part of the claimed design.
